UNITED STATES PATENT OFFICE.

LEWIS HOWES JOHNSON, OF BLOOMFIELD, NEW JERSEY, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,227,153.

Specification of Letters Patent. Patented May 22, 1917.

Application filed September 7, 1915. Serial No. 49,231.

To all whom it may concern:

Be it known that I, LEWIS HOWES JOHNSON, a citizen of the United States, residing at Bloomfield, in the county of Essex and 5 State of New Jersey, have invented certain new and useful Improvements in Telephone-Exchange Systems, of which the following is a full, clear, concise, and exact description.

This invention relates to telephone exchange systems, and more particularly to 10 such systems of the central energy type.

In telephone exchange systems heretofore used, provision has been made whereby an operator is prevented from listening to the 15 conversation of both parties of an established connection. In such systems, should either of the connected subscribers signal the operator by flashing the respective supervisory signal device, it is impossible for 20 the operator to telephonically connect the central office telephone set to the line without first withdrawing one or the other of the plugs from the jack. This results in considerable confusion and is objectionable, due to 25 the fact that the connection between the two subscribers is interrupted.

It is an object of this invention to provide a telephone exchange system in which the above mentioned disadvantage is overcome, 30 and in which, while the operator's telephone set is normally disconnected from an established connection, still either party to an established connection may permit the operator to listen-in.

In accordance with a feature of this invention, there is provided the usual link circuit for interconnecting the subscribers and an operator's telephone set which is normally disconnected from the link circuit 40 forming a portion of an established connection. A relay which is associated with the link circuit is controlled from either of the connected substations and co-operates with operator's control switching means to connect the operator's telephone set to the link circuit.

For a more complete understanding of this invention reference is made to the accompanying drawing showing one embodiment thereof, and wherein all apparatus is 50 shown in its normal and unactuated condition.

In the drawing there is shown the usual subscribers' stations A and B, terminating

at a central office at which is located a cord 55 circuit C for interconnecting the stations. Subscriber A, wishing to converse with subscriber B, signals the operator in the usual manner. The operator answering, inserts the answering plug into the jack of the calling line, causing the operation of supervisory relay 5 included in bridge of the talking strand of the cord circuit; also operates cutoff relay 6. Relay 5, in operating, causes the operation of listening relay 7, which connects 60 the operator's telephone set across the talking strands of the cord circuit. The operator, finding that subscriber A desires to be connected with subscriber B, inserts the calling plug of the cord circuit into the jack of B's line, thereupon operating relay 8 and cutoff relay 9. The operation of relay 8 releases listening relay 7, thereby disconnecting the operator's telephone set from the talking strands of the cord circuit, and lights calling 65 supervisory lamp 10. The operator by actuating ringing key 16 causes the operation of the signal receiving device 15 at station B. In response to the signal, subscriber B removes the receiver from the switch hook, 70 thereby operating supervisory relay 17 which effaces the calling supervisory signal 10 and completes the circuit for relay 18. Relay 18 thereupon operates and completes 75 a locking circuit for itself from battery, through contact 22 of key 23, and contact 24 and winding of relay 18 to ground. The operation of relay 18 also opens at contact 25 the short-circuit about the left-hand winding of relay 26.

Should either A or B, for any reason, desire to signal the operator, this may be done by moving the substation switchhook down and up several times, thereby causing the corresponding supervisory lamp to flash. 95 When the line circuit of either A or B is opened by the first downward movement of the switchhook, the respective supervisory relay is deenergized, whereupon a circuit is completed for relay 26 from battery, through one or the other of the supervisory lamps, the back contact of one or the other of the supervisory relays, the left-hand winding of relay 26, the contact 30 of key 23, and the upper contact of relay 8 to ground. Relay 100 26 operates, completing a locking circuit for itself, which is under the joint control of key 23 and relay 7. The operator having ob-

served the flashing of the supervisory lamp, actuates key 23, thereby causing the operation of the listening relay 7 which connects the operator's telephone set to the talking strands of the cord circuit. This energizing circuit of relay 7 may be traced from battery, through contact 31 of relay 26, both windings thereof, contact 32 of key 23, and the winding of relay 7 to ground. When key 23 is actuated, the locking circuit of relay 18 is opened, whereupon it releases. Upon the operation of listening relay 7 in series with relay 26, a locking circuit is completed for the former which may be traced from the battery through contact 35 of key 23, and contact 36 and winding of relay 7 to ground. This short circuits and releases relay 26. The operator, after conversing with the connected subscriber who has signaled the central office, releases key 23, whereupon listening relay 7 is deenergized. When the conversation between the subscribers is completed, the restoration of the receivers to the switchhooks causes both supervisory lamps 25 to be lighted to furnish a disconnect signal to the operator. Both plugs are removed from the jacks, whereupon all apparatus returns to normal position.

It will be noted from the above description that by utilizing the present invention a telephone exchange system is provided with secret service, that is, an operator cannot listen to the conversation of both parties to an established connection. However, the operator may connect her telephone set to the talking strands of the cord circuit whenever either of the connected subscribers desires to communicate with the operator.

What is claimed is:

40 1. A telephone exchange system comprising two telephone lines terminating at a central office, a link circuit connecting the lines together, an operator's telephone set normally disconnected from the link circuit, a listening relay for connecting the operator's telephone set with the link circuit, a relay in the link circuit controlled over one of the connected lines, and an operator-controlled switch when actuated coöperating with the 45 second mentioned relay when energized to cause the operation of the listening relay.

50 2. A telephone exchange system comprising two telephone lines terminating at a central office, a link circuit connecting the lines together, an operator's telephone set normally disconnected from the link circuit, a relay in the link circuit controlled over a connected telephone line and energized upon the opening of the line, a locking circuit for 55 the relay established upon the energization thereof, and an operator-controlled switch when actuated coöperating with the energized relay to cause the connection of the operator's telephone set with the link circuit.

3. In a telephone exchange system, in combination subscribers' lines terminating at a central office, a link circuit thereat interconnecting said lines, an operator's telephone set normally disconnected from said link circuit forming a portion of an established connection, a listening relay controlling the connection of said set to said link circuit, a supervisory relay associated with said link circuit controlled from the connected substation, a relay associated with said link circuit energized upon the deenergization of said supervisory relay, the energization of said relay conditioning said listening relay for operation, and operator controlled switching means actuated to cause the operation of said conditioned listening relay.

4. A telephone exchange system comprising two telephone lines terminating at a central office, a link circuit connecting the lines together, an operator's telephone set normally disconnected from the link circuit, a supervisory relay in the link circuit, a second relay therefor energized upon the deenergization of the supervisory relay, an operator-controlled switch, and a listening relay energized upon the actuation of the switch when the second relay is energized to connect the operator's telephone set with the link circuit.

5. A telephone exchange system comprising two telephone lines terminating at a central office, a link circuit connecting the lines together, an operator's telephone set normally disconnected from the link circuit, a supervisory relay in the link circuit, a second relay therefor energized upon the deenergization of the supervisory relay, an operator-controlled switch, a listening relay for connecting the operator's telephone set with the link circuit, and an operating circuit for the listening relay completed upon the energization of the second relay and the actuation of the switch.

6. In a telephone exchange system, in combination subscribers' lines terminating at a central office, a link circuit thereat interconnecting said lines, an operator's telephone set normally disconnected from said link circuit forming a portion of an established connection, a listening relay controlling the connection of said set to said link circuit, a supervisory relay associated with each end of said link circuit and controlled from the respective connected substations, a third relay associated with said link circuit energized upon the deenergization of either of said supervisory relays, a circuit for said listening relay open at two points, one of which is closed by the energization of said third relay, and operator controlled switching means, the actuation of which completes the circuit of said listening relay.

7. In a telephone exchange system, in

combination line circuits extending from subscribers' stations to a central office, a link circuit thereat connecting the lines, an operator's telephone set, means at the central office normally excluding the operator's telephone set from the link circuit while the connected line circuits are closed at the subscribers' substations, and means controlled from the subscriber's station of either con-

nected line circuit for rendering the excluding means ineffective to permit the connection of the operator's telephone set to the link circuit while the connected line circuits are closed at the subscribers' stations.

In witness whereof, I hereunto subscribe my name this 3rd day of September A. D., 1915.

LEWIS HOWES JOHNSON.
